ANTENNA STAY ARRANGEMENT

Wilhelm Peters, Berlin, Germany, assignor to
Telefunken Gesellschaft für Drahtlose Tele-
graphie m. b. H., Berlin, Germany, a corpora-
tion of Germany

Application November 19, 1938, Serial No. 241,347
In Germany November 24, 1937

5 Claims. (Cl. 250—33)

The invention is concerned with an arrangement designed to stay antenna masts or poles in a way so as to render them upset-proof, especially for self-radiating mast antennae. Antennae, whether for sending or receiving, must be of a certain height. A recent development in the art has been the use of self-radiating iron masts of great height for sending. They are generally supported and stayed by cables. For the prevention of resonance of the cables or stays with the transmitted wave, they are divided by insulators spaced predetermined distances apart. Where large radiation antenna currents are dealt with, the antenna masts present a high potential to ground. This makes the conditions or duties for the strain insulators particularly severe, for occasionally working voltages over 100 kilo-volts are encountered.

Inasmuch as the field intensity, especially in the neighborhood of these rod or bar-shaped antenna drops sharply with distance, the insulator located in the immediate neighborhood of the antenna is subject to particularly high voltage stresses. Hence, its flashover distance must be made especially long. Moreover, the demand is that its capacitance should be as low as possible in order that stray or parasitic currents in the stay cables may be minimized. From an electrical viewpoint, pin or rod insulators are most preferable, for there is no doubt that they satisfy the requirements most closely, in contrast to what is true of transom suspension or strain arrangements comprising egg or saddle type insulators.

However, from the mechanical viewpoint certain objections arise against the use of rod or pin type insulators for in the event of breakage of such insulators the connection between the mast and the stay cable is severed, with the result that the mast may tumble down. As a matter of fatigue, insulators will be destroyed not only as a result of fatigue in the material, but also due to heat and cold strains in violent changes of weather or also by lightning discharges.

The breaking strength may be enhanced by overdimensioning the insulator or by arranging two or even more insulators in parallel in the same way as is done in the breakproof suspension of power wires. However, arrangements of this kind not only are expensive, but there is a risk of greater leakage, especially in the event of ice and sleet.

The present invention is predicated upon the unlikelihood of the insulators in the various stay-

ing cables suffering breakage simultaneously. In other words, the essential feature of the invention is that in the case of rupture or breakage of an insulator, to rely upon the insulators in the other stay, ropes or cables to assist in the safe supporting of the mast in order to prevent the mast from upsetting or tumbling down.

Figures 1 and 2 show an exemplified embodiment of the invention in elevation and plan, while Figures 3 and 4 illustrate a modification of the invention in elevation and plan, while Figure 5 illustrates the use of the arrangement of Figure 4 for voltage measurement. In Figure 1, the mast 1 is erected on and insulated from ground. It is held in the proper position by the aid of the span or stay ropes or cables 2, 3, 4. The stay or span cables are attached to the mast by the aid of stick insulators 5, 6, 7, while in addition they are inter-connected by the accessory or auxiliary cables 8, 9, 10, at points immediately below the insulators.

Now, in case of breakage of an insulator, say, insulator 6, the stay cable 3 which is directly affected, will still stay connected with the mast by way of the cross cables 8 and 10 with the ring line and the insulators 5 and 7 with the mast. This will preclude all risk of such serious an accident as tilting or tipping over. All that will happen is that the mast may assume a slightly sloped or leaning position; but it will still stay in operating condition. The replacement of the faulty insulator may then proceed with all necessary care and without hurry, and the work is not attended with particular difficulty because the heavy span rope or cable stays are still in place, in fact, the mast is restored to its regular position to mount a new insulator by means of an auxiliary rope. If desired, the ring line may be divided by insulators. Finally, in case of consecutive breakage of all insulators, the holding or staying of the mast may be effected with the span ropes by the aid of distinct catch hooks 11, 12, 13, as indicated in the drawing. In order to render the tensile stress set up in catching more gentle, spring elements may be inserted in the span ropes.

However, the invention here disclosed offers certain advantages also in electrical respect. As pointed out above, the electrical field of the aerial which arises between it and the ground, exhibits a particularly steep drop in the vicinity of the mast. The result is that the voltage drop at the insulators in the neighborhood of the mast is particularly high. Due to the convenient capacitance of this ring to the antenna mast, by

choosing suitable cable diameters of the ring rope (8, 9, 10), the drop of potential at the first insulator may be diminished. In fact, by the aid of additional rings, such as that formed by the cross-connecting cables 8', 9' and 10' along the span ropes disposed after additional strain insulators or terminal insulators, the whole voltage drop may be given a form satisfying any law so as to result in any desired uniform rate of voltage drop. The stray or parasitic currents may be cut down by multiple insulation along the stay cable. To relieve the uppermost and most heavily loaded insulator of electrical stress results in a by no means unessential technical advantage inasmuch as the flashover length or distance of the insulator, especially in the case of high-frequency, rises much more markedly than the potential so that at this particularly endangered point, by the ways and means already mentioned, it becomes possible to choose a smaller insulator which may be manufactured so as to withstand high breaking stresses without any difficulties. Another scheme would be to mount corona rings on the insulators to shape the electrical potential gradient at will. However, they would have to be of considerable size to be effective and, as a result, the mechanical stress rises and the danger due to ice and sleet increases.

Another exemplified embodiment according to the invention is illustrated in Figures 3 and 4. To secure the span ropes or stay cables there is here employed an insulator comprising two conical halves 14, 15, which entirely surrounds the mast, and which is fastened to the latter by the aid of supporter rings 16, 17. The equator line of the resultant double cone structure is surrounded by a metal ring 18 to which the span ropes are fastened by means of hooks.

Finally, the arrangement may also be used for the measurement of the electrical field on the mast in that, as shown in Figure 5, a measuring instrument A is mounted between the mast and the ring conductor surrounding the mast, the said instrument to indicate the charge current or the potential difference.

I claim:

1. An antenna comprising a vertical radiating mast, a plurality of stay cables for supporting said mast, said cables being connected to said mast

through insulating means, an auxiliary supporting means connecting said stay cables at the upper ends thereof whereby the breakage of said insulating means will not disconnect the stay cable associated therewith from said mast, said auxiliary supporting means being so disposed with respect to said mast that a predetermined potential gradient is maintained in the vicinity of said mast.

2. Arrangement as claimed in claim 1, with the characteristic feature that for the measurement of the field intensity or potential a measuring instrument is interposed between mast and the auxiliary supporting means.

3. An antenna comprising a vertical radiating mast, insulating means connected to said mast at a point nearest its top, stay cables connected between said insulating means and the ground and means connecting the upper ends of said stay cables together whereby in the event of the failure of said insulating means between the mast and a stay cable, said cable is maintained in position, said connecting means being so disposed with respect to said mast that a predetermined potential gradient in the vicinity thereof is maintained.

4. An antenna comprising a vertical radiating mast, a plurality of stay cables for supporting said mast, said cables being connected to said mast through insulators and a plurality of auxiliary supporting means connecting said stay cables at the ends of said insulators remote from said mast whereby the breakage of an insulator will not disconnect the stay cable associated therewith from said mast, said auxiliary supporting means being so disposed with respect to said mast that a predetermined potential gradient is maintained in the vicinity of said mast.

5. An antenna comprising a vertical radiating mast, a plurality of stay cables for supporting said mast, said cables being connected to said mast through insulators and a plurality of conducting rings connecting said stay cables at predetermined positions along said cables, said cables being electrically discontinuous between said conducting rings whereby a predetermined potential field about said mast is maintained.

WILHELM PETERS.
